US00D836741S

(12) **United States Design Patent** (10) **Patent No.:** **US D836,741 S**
(45) **Date of Patent:** **** Dec. 25, 2018**

(54) **MODEL OF AN ANATIDAE PORTION**

(71) Applicant: **Contact Left, LLC**, Seattle, WA (US)

(72) Inventors: **John D. Denney, Jr.**, Seattle, WA (US);
Vas Obeyesekere, Seattle, WA (US);
Robert Carrasca, Seattle, WA (US)

(73) Assignee: **Contact Left, LLC**, Seattle, WA (US)

(**) Term: **15 Years**

(21) Appl. No.: **29/608,858**

(22) Filed: **Jun. 26, 2017**

(51) LOC (11) Cl. **21-02**

(52) U.S. Cl.

USPC **D21/808**

(57) **CLAIM**

The ornamental design for a model of an anatidae portion, as shown and described.

DESCRIPTION

FIG. 1 is a perspective view of a model of an anatidae portion showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines in FIGS. 1, 2, and 4-6 illustrate portions of the model of an anatidae portion which form no part of the claimed design.

1 Claim, 7 Drawing Sheets
